(57) **CLAIM**

The ornamental design for packaging container, as shown and described.

DESCRIPTION

FIG. 1 is the 1st perspective view of a packaging container, showing my new design;

FIG. 2 is the 2nd perspective view thereof;

FIG. 3 is a front elevational view thereof;

FIG. 4 is a rear elevational view thereof;

FIG. 5 is a left side elevational view thereof;

FIG. 6 is a right elevational view thereof;

FIG. 7 is a top elevational view thereof;

FIG. 8 is a bottom elevational view thereof; and,

FIG. 9 is a reference view during usage.

The broken lines in FIGS. 1 and 7 drawings depict portions of the packaging container that form no part of the claimed design.

The broken lines shown in FIG. 9 depict environmental structure only and form no part of the claimed design.

1 Claim, 9 Drawing Sheets
